UNITED STATES PATENT OFFICE.

ENOS L. WALKER, OF ST. LOUIS, MISSOURI.

BASKET-HANDLE FASTENER.

SPECIFICATION forming part of Letters Patent No. 729,981, dated June 2, 1903.

Application filed February 3, 1903. Serial No. 141,774. (No model.)

To all whom it may concern:

Be it known that I, ENOS L. WALKER, a citizen of the United States, residing at St. Louis, State of Missouri, have invented certain new and useful Improvements in Basket-Handle Fasteners, of which the following is a specification containing a full, clear, and exact description, reference being had to the accompanying drawings, forming a part hereof.

10 My invention relates to basket-handle fasteners; and it consists of the novel construction, combination, and arrangement of parts hereinafter shown, described, and claimed.

The object of my invention is to provide a fastener for basket-handles by the use of which any one may apply the handle to the basket.

15 In the shipping and packing of the ordinary web baskets it is almost necessary to crate the same, and in order to crate them it is necessary that the handles be removed, and when said baskets are delivered to the consumer it is necessary to provide some cheap and effective manner for fastening the handles to the baskets.

20 In the drawings, Figure 1 is a perspective view of a web basket of the ordinary construction composed of splints and edge bands, showing my invention located on the inside 25 of the basket and secured thereto ready for use. Fig. 2 is a section taken on the line 2-2 of Fig. 1, parts being broken away.

25 Referring to the drawings, 1 indicates the basket proper, 2 the inside band, and 3 the outside band. 4 indicates my invention, which consists of a thin piece of wood provided with a deep elongated recess or cut-out portion 5, forming prongs 6. The thin piece of wood 4 is provided on its lower portion 40 with a tapered edge 7, corresponding to the taper of the inside of the basket, so as to permit the piece of wood 5 to lie closely against the inside wall of the basket. Lying below the recess is an upwardly-tapering edge 8 and 45 a tapering face 9.

50 10 indicates a fastening-wire which passes across the lower portion of the recess 5 in alignment with the tapered edge 8. Said fastening-wire is secured to the wooden piece or strip 4 by means of having its ends inserted

through the prongs 6 and bent as illustrated in Fig. 2. When the wire 10 has been applied to the piece 4, as indicated in Figs. 1 and 2, there is a space between the edge 8 and said wire for the insertion of the handle 55 between the same. The piece 4 is applied to the basket, as illustrated in Fig. 1, wherein the prongs 6 are shown inserted between the inside band 2 and the outside band 3 and is held by the wire clenches 11, which also hold 60 the bands to the splints of the basket.

12 indicates the handle for the basket. The ends of said handle are provided with tapering portions 13, tapering faces 14, and transverse grooves 15. The fastening-wires 10 are 65 adapted to fit in said transverse grooves.

In order to apply the handle 12 to the basket, it being assumed that the fastener has been applied to the basket, as illustrated in Fig. 1, it is only necessary to place the ends 70 of the handle in the recesses 5 between the prongs 6, press down on the same, and insert the tapering portions 13 in between the wire fastening 10 and the tapered edges 8 and press down on the handle until the fastening- 75 wires 10 have been seated in the transverse grooves 15. It may be noted in this connection that the recess 5 is of sufficient width to receive the ends of the handle and that each side of the basket is provided with a fastener, 80 such as heretofore described. The prongs 6 will also act as a lateral brace for the handle, and when the fastening-wires 10 have been seated in the grooves 15 the handle is fastened 85 in position and ready for use and cannot be withdrawn from the basket without breaking the fastening-wire 10. When the baskets are shipped to the consumer, the handle 12 is removed and sent along with the baskets, and when the consumer desires to apply the handle 90 to the basket it is easily done, as heretofore described.

Having fully described my invention, what I claim is—

A basket comprising plates each provided 95 with a recess, the lower wall of which is provided with a tapering face, a handle the ends of which are adapted to be inserted in said recesses, the ends of said handle being provided with transverse grooves and tapering 100

faces to fit the tapering faces formed in said plates, and a fastening-wire spanning each of said recesses in proximity to said tapering faces and adapted to be inserted in said 5 grooves when the handle is applied to the basket and pressed downwardly in said recesses, substantially as specified.

In testimony whereof I have signed my name to this specification in presence of two subscribing witnesses.

ENOS L. WALKER.
